UNITED STATES PATENT OFFICE.

VERNE C. KENNEDY AND MILLARD B. KENNEDY, OF CANTON, SOUTH DAKOTA.

APPARATUS FOR TREATING POLES.

1,259,025.

Specification of Letters Patent. Patented Mar. 12, 1912.

Application filed June 8, 1917. Serial No. 173,834.

To all whom it may concern:

Be it known that we, VERNE C. KENNEDY and MILLARD B. KENNEDY, citizens of the United States, residing at Canton, in the county of Lincoln and State of South Dakota, have invented certain new and useful Improvements in Apparatus for Treating Poles, of which the following is a specification:

10 This invention relates to preserving apparatus, particularly to apparatus for treating wooden poles, such as telegraph poles, with preservatives, and has for its object the provision of a novel form of apparatus whereby poles may be treated with a preservative under pressure for only a short distance above and below the ground line.

15 An important object is the provision of an apparatus of this character in which the treatment takes place within an air-tight tank completely inclosing the entire poles.

20 A further object is the provision of such an apparatus so designed that the minimum amount of preservative may be applied, thus reducing waste and also the expense.

25 Other objects and advantages, such as simplicity in construction and operation, cheapness in manufacture, efficiency in service, and the general improvement of the art, will become apparent during the course of the following description taken in conjunction with the accompanying drawing, in which:

Figure 1 is a vertical longitudinal sectional view of the apparatus, and

35 Fig. 2 is a cross-sectional view therethrough.

Referring more particularly to the drawing, the numeral 1 designates a tank, preferably cylindrical in shape and provided 40 with an air-tight fitting cover 2 held in position by any suitable means, such as the clamps 3.

45 Adapted to be disposed within the tank 1 is a partition plate 4 provided with any suitable or desired number of circular holes 5, through which the poles 6 are adapted to be passed. At each of the holes there are pivoted, as at 7, similar semicircular ring members 8 having their free ends outwardly 50 turned at 9 and adapted to be held together by suitable clamp members 10. Packing rings or strips 11 of felt or other suitable material are disposed between the poles 6

and the clamping ring sections 8, for forming a tight joint about the poles.

55 A pipe 12 communicates with the tank 1 at its upper end and is adapted to supply air under pressure to the interior of the tank. A similar pipe 13 communicates with the lower portion of the tank, both of these pipes being provided with suitable valves 14 and 15. Another pipe 16 communicates with the tank 1 at a considerable distance above the bottom thereof, and is provided with a cut-off valve 17, this pipe being for the purpose of supplying the preservative into the tank. An outlet pipe 18 provided with a valve 19 communicates with the tank 1 immediately above the plate 4 and leads back to the reservoir containing the liquid. 70 At its extreme bottom the tank has communicating with its interior a drain pipe 20 having a valve 21.

75 The operation of the device is as follows: The cover 2 being open, the poles 6 are lowered into the tank 1 in any suitable manner and are passed through the holes 5. Access to the interior of the tank is had by means of a manhole 22 closed by a suitable door 23.

80 Through this manhole the operator then places the packing members 11 about the poles, swings the ring sections 8 together and then secures them by the clamping members 10, making tight joints about the poles. The poles are so positioned vertically that their intended ground line is at a point a desired distance above the partition plate 4. The manhole cover 23 is then closed, as is also the cover 2 of the tank. 85

85 The preserving liquid is allowed to flow through the pipe 16 into the tank to a depth which will cover the desired length on the poles. At the same time, the valves 14 and 15 are opened and compressed air supplied to the tank above and below the partition 90

95 plate 4. In order that the liquid may not leak down around the poles and around the plate 4, the pressure below the plate 4 should be always greater than that supplied to the tank above the plate. The pressure above 100 the partition will force the preservative into the wood and will cause that portion of the pole between the partition plate and the top of the preserving liquid to become impregnated. After the operation is completed 105 the liquid may be drawn off through the

pipe 18 and returned to the reservoir for the next treatment. If by any chance any small amount of liquid might leak into the space below the plate 4, it may be drained off through the pipe 20.

From the foregoing description together with a study of the drawing it will be apparent that we have thus provided a simple and efficient device whereby poles of any 10 length may be treated with preserving liquid of any kind for a desired distance intermediate their ends, and at any desired pressure, thus effecting a great saving in material and still rendering the poles unsusceptible to moisture.

It will be understood that we reserve the right to make such changes in the form, construction and arrangement as will not depart from the spirit of the invention and 20 which will be within the scope of the subjoined claims.

Having thus described our invention, we claim:

1. An apparatus for treating wooden 25 poles with a preservative comprising a tank, a cover therefor forming an air tight receptacle, a partition plate dividing said tank into upper and lower compartments, said plate being provided with holes for the passage of poles to be treated, clamping members on said plate engaging the poles, packing members between said clamping members and the poles forming liquid-tight joints, a feed pipe discharging into the upper 30 compartment whereby a preservative liquid may be introduced to a desired depth upon said partition plate, and a compressed air conducting pipe communicating with

said upper compartment above said first named pipe, and a drain pipe communicating with said upper compartment adjacent said partition plate. 40

2. An apparatus for treating wooden poles with a preservative, comprising a tank, a partition plate within said tank provided with holes for the insertion therethrough of poles to be treated, clamping members on said plate surrounding said holes and engaging the poles for holding them at selected heights above the bottom of the tank, packing strips disposed between said clamping members and said poles and forming liquid-tight joints, a pipe for supplying a preservative liquid into said tank above said partition plate, and a drain pipe. 45 50 55

3. An apparatus for treating wooden poles with a preservative, comprising an air tight tank, a partition plate therein dividing the tank into upper and lower compartments, said partition plate being provided with holes for the passage of poles to be treated, means for forming liquid-tight joints at the junctures of said poles with said partition plate, said means further supporting said poles at selected distances above the bottom 60 65 70 of the tank, means for supplying a preservative liquid within the upper compartment to a selected height above said partition plate, and a compressed air conducting pipe communicating with the upper compartment for applying pressure upon the preservative liquid therein. 75

In testimony whereof we hereto affix our signatures.

VERNE C. KENNEDY.
MILLARD B. KENNEDY.
